UNITED STATES PATENT OFFICE.

JOSEPH A. IMHOF, OF NEW YORK, N. Y., ASSIGNOR TO INVISIBLE COLOR PRINT CORPORATION, OF NEW YORK, N. Y., A CORPORATION OF NEW YORK.

ART OF PRINTING.

Application filed April 7, 1922. Serial No. 550,305.

To all whom it may concern:

Be it known that I, JOSEPH A. IMHOF, a citizen of the United States, and a resident of New York city, in the borough of Manhattan, county and State of New York, have invented certain new and useful Improvements in the Art of Printing, of which the following is a specification.

This invention relates to the art of printing and has for its main feature and object the printing of a picture or other matter in an apparently uniform color but having latent and substantially invisible color that is released and made visible upon application to the printed surface of a solvent, such as water. The solvent may be applied to the printed surface by means of a brush and each colored part may be separately developed but preferably the latent color is so applied that it covers substantially the entire printed surface and upon the application thereto of a solvent, each of the particles of coloring matter distributed over the surface will release just enough color to cover the immediately adjacent surface, so that immersion of the printed surface in water will develop all the colors and will retain the colors in the proper place appropriate to the picture or design to be produced.

The process of producing prints of this character is disclosed in Patent No. 1,384,663 of July 12, 1921 granted to me.

Figure 1 is a view of a complete picture as it will appear after successive superimposed impressions have been made.

Fig. 2 is a view of a partial image of the picture in Fig. 1 having latent blue coloring matter.

Fig. 3 is a view of a partial image of the picture in Fig. 1 having latent yellow coloring matter.

Fig. 4 is a view of a partial image of the picture of Fig. 1 having latent red coloring matter.

Fig. 5 is a view of a partial image of the picture of Fig. 1 devoid of latent coloring matter and printed in insoluble ink that acts as a dam between differently colored parts of the picture to prevent intermingling of the colors.

Fig. 6 is a view of a surface containing a dam of varnish or other insoluble material applied to the picture to prevent intermingling of colors.

Fig. 7 is a view of a surface having still another form of dam of varnish, ink or other insoluble material to prevent or disguise overflow of color. 55

In preparing the picture, the artist makes separate drawings of the blue, yellow and red partial images as shown in Figs. 2, 3 and 4. These drawings are however made in black or other uniform color, and are reproduced by means of photo-engraving and made into half tone plates or their equivalent such as plates made by the Ben Day process. Three separate impressions are then superimposed on the same surface resulting in the picture shown in Fig. 1. In printing the several partial images soluble 60 anilin color is ground in, or otherwise thoroughly mixed with, the insoluble ink of uniform color, blue for the partial image of Fig. 2; yellow for the partial image of Fig. 3 and red for the partial image of Fig. 4. 65

It has been found that a practically perfect disguise may be obtained by mixing in addition to the insoluble ink and the coloring matter a second insoluble ink of a color 70 different from the first mentioned insoluble ink and different from the coloring matter. For instance, the ink used to print the blue image of Fig. 2 may have mixed with it a certain amount of red oil ink; the ink used 75 to print the yellow image of Fig. 3 may have a certain amount of blue oil ink; and the ink used to print the red image of Fig. 4 may have a certain amount of blue oil ink. The result of adding the insoluble colored ink 80 is to obtain a substantially uniform tone on the picture shown in Fig. 1 before development, thereby rendering detection of the latent color practically impossible. 85

A preferred formula for mixing the ink 90 for producing such a design is as follows: for the yellow image, 14 parts aniline yellow, 3 parts blue oil ink, 5 parts black oil ink and necessary varnish to make workable; for the red image, 8 parts aniline red, 4 95 parts black oil ink, 6 parts blue oil ink, and necessary varnish to make workable; for the blue image, 14 parts aniline blue, 4 parts red oil ink, 4 parts black oil ink, and necessary varnish to make workable. 100

To all appearances, therefore, a picture uniform in color is produced by the superimposing and partial overlapping of the 105

partial images. These partial images contain components of light and shade and of latent color, and, where overlapping of partial images occurs, as in the case of the face

5 1 of the boy, or of the oranges 2 on the tray, regard must be had to the total effect of light and shade in overlapping parts of the image. That is to say, the sum of the shade and light components of overlapping 10 parts must equal the correct amount of light and shade in the complete picture, and the artist must therefore not put the complete shade and light in a partial image where overlapping occurs. Thus in Figs. 3 15 and 4 each incomplete image carries an incomplete component of light and shade in the face 1 and oranges 2. But here another factor enters. We are dealing not merely with incomplete components of light 20 and shade but also with the superimposing of colors and the amount of light and shade of each partial image depends not merely upon the number of partial images that are necessary to produce a complete image but 25 also upon the amount of coloring matter to be supplied by a partial image. Thus in the case of the oranges 2, the amount of yellow required is considerable as shown by Fig. 3, while the amount of red required, as 30 shown by Fig. 4, is slight. The proportion of shade of partial image Fig. 3 is therefore greater than the proportion of shade of partial image Fig. 4, so far as oranges 2 are concerned. In other words, where overlapping 35 occurs, the total amount of shade required is divided in proportion to the amount of latent color required to be carried in the several partial images, because the insoluble ink carries the soluble coloring 40 matter.

In some instances it is preferred to add, to the three superimposed impressions heretofore mentioned, an impression like that shown in Fig. 5. This impression constitutes a dam of insoluble material between the different partial images. This dam may, as in the example shown, constitute a part of the design of complete image and may therefore be printed with insoluble ink. If a 45 dam such as is shown in Fig. 5 is used printed with insoluble ink, it is desirable to add a sufficient amount of red oil ink so that this impression also will match the general tone effect of the three other impressions. In other cases where the character of the design does not lend itself to having a dam in dead black or other uniform color, said dam may be printed in insoluble varnish, or other material that will be practically invisible.

In Fig. 6 is shown a dam of insoluble varnish which is in the form of an outline surrounding the picture and also separating the constituent parts of the pictures. This 55 dam is practically invisible. In Fig. 7 the

dam, which may be of insoluble ink or insoluble varnish, is a solid mass surrounding the design of Fig. 6.

By the process above described singularly beautiful effects may be produced, and it is 70 a remarkable fact I find that the pictures may be developed by immersion substantially without intermingling of colors. This is facilitated in some instances by retarding the solution of the soluble coloring matter 75 of the different partial images. This may be accomplished by mixing gum arabic with the soluble coloring matter in different proportions so that upon immersion successive color releases are obtained. It is also im- 80 portant that hard coated paper be used on which to print the image if the best results are to be obtained. I prefer to use a smooth finish or coated stock.

I claim:

1. As a new article of manufacture, a design, produced from half-tone plates or the like, of apparently uniform color but carrying soluble coloring matter in substantially invisible form comprising: a plurality of 90 partial images printed in superimposed and partially overlapping relation with insoluble ink of a substantially uniform color the insoluble ink of the several partial images containing differently colored soluble 95 coloring matter, the overlapping of the coloring matter producing requisite latent coloring other than that of the primary colors.

2. As a new article of manufacture, a design, produced from half-tone plates or the like, of apparently uniform color but carrying soluble coloring matter in substantially invisible form comprising: a plurality of 100 partial images printed in superimposed and partially overlapping relation with insoluble ink of a substantially uniform color the insoluble ink of the several partial images containing differently colored soluble coloring matter, the overlapping of the insoluble 105 ink producing requisite light and shade and the overlapping of the coloring matter producing requisite latent coloring other than that of the primary colors.

3. As a new article of manufacture, a design of apparently uniform color but carrying soluble coloring matter of various colors in substantially invisible form comprising: a plurality of partial images printed to 115 form a picture, each partial image printed with insoluble ink of a given color having an admixture of soluble coloring matter of a different color and insoluble ink of still another color.

4. As a new article of manufacture, a 120 design of apparently uniform color but carrying soluble coloring matter of various colors in substantially invisible form comprising: a plurality of partial images printed to form a picture, each partial image 125

65 130

printed with insoluble ink of a given color having an admixture of soluble coloring matter of a different color and insoluble ink of still another color, the first mentioned ink being of a uniform color in all of the partial images, the coloring matter of each partial image being of a color contrasting with the coloring matter of the other partial

images and the last mentioned insoluble ink being of a color in each partial image corresponding to the soluble coloring matter of one of the other partial images. 10

Signed at New York city, in the borough of Manhattan, county and State of New York, this 6 day of April, 1922.

JOSEPH A. IMHOF.
